United States Patent Office.

D. S. BAKER, OF WEST BLOOMFIELD, NEW YORK.

Letters Patent No. 81,729, dated September 1, 1868.

IMPROVED BRAKE FOR MACHINERY.

The Schedule referred to in these Letters Patent and making part of the same.

TO ALL WHOM IT MAY CONCERN:

Be it known that I, D. S. BAKER, of West Bloomfield, Ontario county, in the State of New York, have invented a new and improved Brake; and I do hereby declare that the following is a full and exact description thereof, reference being had to the accompanying drawings, and to the letters of reference marked theron, in which like parts are represented by like letters in the several figures.

The nature of my invention consists in the arrangement and combination of certain parts, to be hereafter described, whereby to prevent any retrograde motion of any machine or attached wheel, particularly where a reverse or backward motion would operate injuriously.

To enable others skilled in the art to make and use my invention, I will proceed to describe its construction and operation.

In the drawings—

Figure 1 represents an elevation of my device, and

Figure 2 an enlarged vertical section (longitudinally) of the brake.

A represents any support for my device.

B and C, wheels, attached to a shaft, F, the former of which may be a balance or band-wheel.

The periphery of C, the smaller one, is covered with a ring or band of rubber, α , secured by a suitable groove in said wheel, or in any other desirable way to hold it, or it may be attached to the side of the rim, or a grooved flange attached to the side of the wheel, at any desired distance from the periphery, thus enabling the wheel C to be used for a band-wheel.

D is a block, secured to support A, and to this is fastened a spring, b , the inner end of which carries a triangular-shaped frame, consisting of two metallic checks, attached to and oscillating about b , as seen at e , so as to vary the inclination of E.

The inclination of b may also be varied to regulate the friction on rubber band α , by raising the outer end of spring b , as seen at i , fig. 2.

d is a friction-roller, secured to the lower outer ends of the checks of frame E, and bears upon the periphery of band α , which, when the wheel is revolving, as shown by the arrows in fig. 2, d , revolves, as shown by the arrow over it; and, under these circumstances, the ratchet-teeth t , on the inner ends of checks, are raised, and do not come in contact with the rubber band α .

The friction-roller is so arranged as to permit a limited reverse motion, say, for instance, sufficient to raise the needle of a sewing-machine, or re-thread, thereby saving a stitch, but beyond this, a further reverse motion of C, with its band, α , draws down E, and, its ratchet-teeth coming in contact with α , stops further backward motion.

The whole pressure of the spring b should be upon the friction-roller, keeping it upon the band.

The distance the wheel C can be moved backward can be regulated, that is, increased or diminished, by means of a movable pin, c , passing through checks of E, and which the inner end of b bears up against, so as to increase or diminish the distance from the roller to the spring.

The checks of E are held together by the axle at e , that of d , and pin f .

Having thus described my invention, what I claim as new, and desire to secure by Letters Patent of the United States, is—

A friction-brake, constructed and operated in the manner as shown and described.

D. S. BAKER.
